UNITED STATES PATENT OFFICE.

WALDEMAR KOPS, OF NEW YORK, N. Y., ASSIGNEE TO KOPS BROS., OF NEW YORK, N. Y.
A FIRM.

BRASSIERE.

1,253,052.

Specification of Letters Patent. Patented Jan. 8, 1913.

Application filed October 11, 1917. Serial No. 155,972.

To all whom it may concern:

Be it known that I, WALDEMAR KOPS, a citizen of the United States, residing in the borough of Manhattan, city, county, and State of New York, have invented an Improvement in Brassières, of which the following is the specification.

As heretofore commonly constructed, garments known as brassières have been made so as to open or unhook at the front and in some instances have been provided with suitably adjustable means for properly supporting the busts of the wearer. A garment of this kind for example is illustrated in Letters Patent No. 1,237,059, granted to me August 14, 1917. The object of my present invention is generally the same as the object shown and described in the Letters Patent aforesaid. In the present instance however, in order to obtain a uniform configuration and also to properly and adequately support the busts of the wearer, I provide in my improved garment a continuous or undivided front member, back members adapted at their adjacent edges to be connected to one another, and means for connecting the continuous front member to the back members preferably along the axillary line of the garment so as to adjust the same to a desired position on the body, the adjusting means being brought to the front of the garment, passed through suitable slots provided for this purpose, so that the adjustment may be readily effected.

The garment made in accordance with this invention will be hereinafter more particularly described in conjunction with the accompanying drawing in which:

Figure 1 is a perspective view of the brassière as applied in use, and

Fig. 2 is an enlarged elevation showing the improved brassière from the inner side thereof.

Referring particularly to the drawing, in carrying out this invention I employ a front member 10 which is so shaped as to conform to the configuration of the wearer and is continuous so as to extend entirely across the front of the body terminating at substantially the axillary lines or under-arm portions of the wearer. Together with this continuous front member 10 I employ back members 11 and 12. At one end the front member 10 is provided with a reinforcing strap 13 and at the opposite end with a cor-

responding reinforcing strap 14. The reinforcing strap 13 is provided with a series of eyelets 15 and similarly the reinforcing strap 14 is provided with a series of eyelets 16. The back member 11 at one end is also provided with a reinforcing strap 17 in which there is a series of eyelets 18 corresponding to the eyelets 15 in the reinforcing strap 13, the reinforcing straps 13 and 17 being placed adjacent one another in the parts of the garment as connected for use. At its opposite end this back member 11 is fitted with a reinforcing strap 19 to which there are suitably secured a series of eyes 20. The back member 12 is constructed in a manner similar to that in which the back member 11 is made, it being provided on one end with a reinforcing strap 21 in which there is a series of eyelets 22 corresponding with the eyelet 16 in the reinforcing strap 14, while at its opposite end there is a reinforcing strap 23 in which there is a series of hooks 24 adapted to engage with the eyes 20 to secure the garment on the body of the wearer.

The back member 11 is secured to the continuous front member 10 by a series of laces 25 each of which at one end is passed through an eyelet 15 in the reinforcing strap 13 and suitably secured in place therein. It is also passed through an eyelet 18 in the reinforcing strap 17 while all the opposite ends of these laces 25 are brought together and secured in one end of a tape 26. This tape 26 extends to the lower front portion of the continuous front member 10 where it is passed through one of the slots 28 provided therefor in a strengthening member 27. The back member 12 is secured in the garment in a similar manner, there being employed for this purpose a series of laces indicated at 29. One end of these laces is passed through an eyelet 16 in the reinforcing strap 14 and also through an eyelet 22 in the reinforcing strap 21, while all the opposite ends of these laces are brought together and connected at one end to the tape 30. This tape 30, similar to the tape 26, extends to the front portion of the garment and is passed through the other slot 28 provided therefor in the strengthening member 27 so that the outer or free ends of the tapes 26 and 30 may be tied together after the parts have been adjusted to secure the garment in a desired position on the body of the wearer.

I may also employ shoulder straps indicated at 31 each of which may be suitably connected at one end to the upper portion of the continuous front member 10 and at the 5 other end to one of the back members. Also as indicated in the drawing the back members 11 and 12 may be provided with additional reinforcing straps 32 and the continuous front member may be made in several parts which are suitably joined along the lines of stitching indicated at 33.

In the use of this garment, as no doubt will be understood, the adjustable lacing devices are loosened, the garment placed on the 15 body, and the adjacent edges of the back members connected by the hooks and eyes as shown, or other similar means provided for this purpose. The tapes 26 and 30 are then drawn from the outer ends to adjust 20 the continuous front member to position relative to the back members so as to properly and adequately support the busts of the wearer and the tapes then tied or otherwise secured relatively to one another to maintain 25 the parts of the garment in their adjusted positions.

I claim as my invention:

1. As a new article of manufacture, a brassière comprising a front member, back 30 members, and devices for adjustably connecting the front member to the back members at the axillary line of the garment, which devices extend to and through the lower front central portion of the front member where they are adapted to be connected to one another.

2. As a new article of manufacture, a brassière comprising a front member, back members, means for connecting the adjacent 40 edges of the back members to one another, and lacing devices for adjustably connecting the front member to the back members at the axillary lines of the garment, which lacing devices extend to the lower central portion 45 of the front member where they are adapted to be connected to one another.

3. As a new article of manufacture, a brassière comprising a continuous front member extending from one axillary line 50 to the other, back members, and lacing devices for adjustably connecting the front member to the back members at the adjacent edges thereof, which lacing devices extend

to the lower central portion of the front member where they are adapted to be connected to one another. 55

4. As a new article of manufacture, a brassière comprising a continuous front member extending from one axillary line to the other, back members, means for connecting the adjacent edges of the back members to one another, and lacing devices for adjustably connecting the front member to the back members at the adjacent edges thereof, which lacing devices extend to the 60 lower central portion of the front member where they are adapted to be connected to one another. 65

5. As a new article of manufacture, a brassière comprising a continuous front 70 member extending from one axillary line to the other and shaped to conform with the configuration of the wearer, back members, means for connecting the adjacent edges of the back members to one another, and lacing 75 devices each consisting of a series of laces extending through eyelets provided therefor in the forward edge of a back member and also through corresponding eyelets provided therefor in the adjacent edge of the front 80 member, the said laces extending forwardly to the lower central portion of the front member where they are adapted to be connected to one another.

6. As a new article of manufacture, a brassière comprising a continuous front member extending from one axillary line to the other and shaped to conform with the configuration of the wearer, back members, means for connecting the adjacent edges of 90 the back members to one another, lacing devices each consisting of a series of laces extending through eyelets provided therefor in the forward edge of a back member and also through corresponding eyelets provided 95 therefor in the adjacent edge of the front member, and a tape secured to each series of laces, the said tapes extending forwardly and passing through slots provided therefor in the lower central portion of the front member 100 where the tapes are adapted to be connected to secure the parts in position on the body of the wearer.

Signed by me this 8th day of October, 1917.

WALDEMAR KOPS.
